Attorney

UNITED STATES PATENT OFFICE.

GEORGE BRAIN, OF FOREST CITY, PENNSYLVANIA.

COMB.

SPECIFICATION forming part of Letters Patent No. 623,201, dated April 18, 1899.

Application filed January 31, 1899. Serial No. 703,978. (No model.)

To all whom it may concern:

Be it known that I, GEORGE BRAIN, a citizen of the United States, residing at Forest City, in the county of Susquehanna and State 5 of Pennsylvania, have invented certain new and useful Improvements in Combs for Use on Cats, Dogs, and other Animals; and I do declare the following to be a full, clear, and exact description of the invention, such as 10 will enable others skilled in the art to which it appertains to make and use the same, reference being had to the accompanying drawings, and to the letters of reference marked thereon, which form a part of this specification. 15

The invention relates to combs for use upon cats, dogs, or other animals which are infested with fleas and other vermin at certain seasons of the year.

20 The special object of my invention is to kill the vermin before they have a chance to make their escape.

Figure 1 of the drawings is a perspective view of my comb as an entirety; Fig. 2, a vertical section showing the position of the plate with respect to its pivot, spring, and the handle; and Fig. 3 is a detail view of the side plates bent around the front to form a backing for the comb.

25 In the drawings, A represents the handle, to which are secured the side plates B B, which are bent at right angles and toward each other to form a back for the comb C. The latter may be fastened in any suitable manner to 30 this back and is preferably provided with the

fine teeth a on one side and opposite thereto the coarse teeth a'. Of course the coarse teeth are unnecessary in my comb, as the knots and kinks in the hair may be taken out with any coarse-toothed comb. Between the 40 angle-plates B B, I make fast the cross-pivot d, on which the bottom eyes d' d' of the plate D may turn. On this pivot d is arranged a torsion-spring E, with one end resting on the handle A, while the other rests against the 45 inside face of the plate D.

As the fine-tooth comb C is drawn through the hair of the animal the fleas or other vermin are gathered together on the inside of the comb C and between the plates B B. The 50 operator, who has held the plate D down on the handle with his finger or thumb, now lets go the plate, which is carried by the torsion-spring with considerable force against the comb, thus crushing and killing the vermin 55 which have been combed out. In practice it has been found to operate with great certainty and efficiency.

What I claim as new is—

The handle A, angle-plates B B forming 60 sides and back, comb C, pivoted cross-plate D and spring E arranged to force the plate D against the comb C, substantially as and for the purpose specified.

In testimony whereof I affix my signature 65 in presence of two witnesses.

GEORGE BRAIN.
